(57) **CLAIM**

The ornamental design for a pet toy having an expandable body, as shown and described.

DESCRIPTION

FIG. 1 is a perspective view showing my new design of a pet toy having an expandable body;

FIG. 2 is a front view of the pet toy of FIG. 1 shown in elevation;

FIG. 3 is a rear view of the pet toy of FIG. 1 shown in elevation;

FIG. 4 is a right side view of FIG. 2;

FIG. 5 is a left side view of FIG. 2;

FIG. 6 is a top view of FIG. 2;

FIG. 7 is a bottom view of FIG. 2;

FIG. 8 is another perspective view thereof showing the expandable body partially folded over; and,

FIG. 9 is another perspective view thereof showing the expandable body fully extended.
